RADIO RECEIVING SET

Edward F. Andrews, Chicago, Ill.

Application February 9, 1931, Serial No. 514,350

19 Claims. (Cl. 250—14)

This invention relates to radio receiving sets, and includes the radio cabinet structure described in my co-pending application Serial No. 263,006, filed March 20, 1928.

5 Among the objects of the invention are to provide a radio receiving set of generally elongated form in the vertical direction, and in which the chassis is inserted in the cabinet from the top or bottom; to provide a radio receiving set in which 10 the cabinet is slipped over a chassis which is adapted to rest upon the floor; to provide improved means for securing the cabinet and chassis together; to provide means for the ventilation of the receiving set; to provide an improved cabinet structure for radio sets; and to 15 provide an improved decorative surface covering openings in the cabinet for egress of sound and/or ventilation.

Other objects, advantages and capabilities will 20 appear from the following description of a preferred embodiment of the invention, taken in conjunction with the accompanying drawings, in which

Figure 1 is a front elevational view of a radio 25 receiving set embodying the invention;

Figure 2 is a similar view illustrating the manner in which the cabinet is applied to the chassis.

Figure 3 is a sectional detail view showing the handle construction;

30 Figure 4 is a sectional detail view taken on the line 4—4 of Figure 3;

Figure 5 is a transverse sectional plan view taken on the line 5—5 of Figure 1, and on a reduced scale; and

35 Figure 6 is a sectional detail view taken on the line 6—6 of Figure 5.

Referring to the drawings, the radio set comprises a chassis 10, cabinet 11, and handle 12. The chassis 10 may suitably be formed from a 40 length of channel 13 which is bent to provide a vertical length 14 and a horizontal length 15. This bending may be effected by slitting the side webs and bending the main web along the line 16. The channel lengths 14 and 15 are connected by 45 corner plates 17 which complete the channel members 14 and 15 so as to constitute a strong and rigid chassis.

The side webs of the channel 15 and the corner plates 17 are rigidly secured to a suitable base, 50 which is shown by way of example as two feet members 18, each of which provides two feet 19, located at the corners so as to provide space therebetween for the admission of air, which has an important function in keeping the set cool, 55 as will hereinafter be more fully described. The

feet members 18 carry at each end flanges 20 which may suitably be secured to the side webs of the channel 15 or the corner plates 17 by rivets or other suitable means. The feet members 18 provide shoulders 21 which serve as abutments 5 for the lower edge of the cabinet.

The back of the channel 14 provides a support for a loud speaker 22 of conventional type. This back is provided with a series of openings 23 adjacent the loud speaker so that sound waves generated to the rear of the cone may pass through

the set and be projected from the rear. Above the loud speaker 22 the channel 14 is provided with a shelf 24. The shelf 24 and the back of the channel 15 serve as supports for the mounting 10 of radio tubes 25 and other parts of the set which need not be illustrated or described here.

The shelf 24 and the back of the channel 15 are provided with openings 26 and 27 respectively 15 which permit air to flow upwardly through the cabinet to cool the set. I prefer to mount on the feet members 18 a plate 28 which effectively closes the base of the chassis. This plate is mounted above the floor and is provided with openings 29 whereby cooling air is admitted into 20 the cabinet. The openings 29 are preferably arranged on the side of the plate 28 remote from the speaker 22. The plate 28 has several functions.

It prevents children from access to the wiring and it provides a separator of substantial 25 dimension between the sound waves from the opposite sides of the loud speaker, insuring improved sound reproduction, particularly in the case of low notes.

The cabinet 11 comprises a metal top wall 30 30 which is dished so as to provide a depending flange or skirt 31. The top 30 may suitably be

substantially rectangular in shape, the corners being bevelled or cut away as shown in the drawings.

At each corner of the top 30 is secured, 40 for example by riveting or other suitable means, a depending strip 32 which may be of flared channel form so as to cooperate with the sides 33 of the cabinet. The sides 33 may suitably be

made of corrugated board, pulp wood, or other 45 material of good acoustic properties. Since the top 30 and corner strips 32 reinforce the cabinet, the sides 33 need not be made of strong material.

The four sides 33 may be formed integrally, for example from a piece of corrugated 50 board and may be folded up in compact form until the set is assembled. This may be done by opening the sides 33 into substantial rectangular or tube-like relation and inserting same so as to bring its corners into engagement with the 55

corner strips 32. The sides 33 may be first assembled in the form of a tube or two free edges may be placed in abutment behind one of the corner strips 32. The walls 33 may be secured to the cabinet frame members 30 and 32 by a metal strap 34 which is connected to the corner straps 32 at their lower edges by bolts, rivets, or the like 35 which pass through the strap 34, corner straps 32 and walls 33.

10 The front wall 33 of the cabinet is provided with openings 36 adapted to register with the interior of the loud speaker cone. The opposite wall 32 is provided with openings 37 which permit the sound waves from the rear of the speaker to pass outwardly through the rear wall. In

15 order to obscure the openings 36 and 37 from view, I prefer to apply over the exterior of the walls 33 suitable fabric, preferably of an open weave. I have found burlap, preferably dyed to a desired color, to be very suitable for this purpose. The burlap may be secured or applied to the walls 33 in any suitable manner before the same are assembled in the cabinet structure. For example, I may secure the fabric to the surface of the wall unit by means of a suitable adhesive, bringing the exposed edge or edges into a position where they will be hidden by one of the corner strips 32. I may use glue or the like as the adhesive, or I may use 20 cellulose dope, which has waterproofing as well as adhesive qualities.

30 The cabinet top 39 is provided with openings 38 which permit the escape of the heated air which passes upwardly through the cabinet. These openings are located near the center of the top 39 so that they may be conveniently covered or hidden by suitable means, for example the means hereinafter more fully described. The channel member 14 may terminate short of the top 39 in order to permit free escape of air from 35 both sides of the channel, or the back of the channel may be provided with perforations 39 for that purpose.

40 Instead of or in addition to the openings 38, I may provide openings 40 near the upper ends of the walls 33 for the escape of the heated air. These openings 40, like the openings 36 and 37, are hidden from view by the fabric covering and need not be artistically shaped or carefully finished. They may suitably be cut by a die in appropriate number.

45 In order to avoid an excessively utilitarian appearance, the handle 12 by means of which the set may be moved from place to place, is preferably formed as an ash tray, the horizontal member 41, which is engaged by the hand, being shaped to serve as a cigar rest. The horizontal member 41 gives into a vertical stem 42 which carries the tray 43. The underside of the tray 50 55 is provided at its center with a boss or shoulder 45 which is adapted to engage the top 39 so as to maintain the underface of the tray in spaced relation to the top 39 so that air may escape from the openings 38.

60 65 The boss 45 carries a downwardly extending stem 46 which is adapted to enter a central opening 47 of the top 39 so as to enter a socket 48 carried by a bracket 49 which is mounted on the upper end of the channel member 14. The 70 socket is provided with grooves 50 through which pins 51 carried by the stem 47 are adapted to pass when the handle is being applied. The underface of the socket 48 is provided with grooves 52, located angularly with respect to the grooves 75 50, adapted to receive the pins 51 as shown in

Figure 3 and lock the handle in position. The relation of the chassis 10 and cabinet 11 is such that the lower edge of the cabinet bears against the shoulders 21 and the cabinet top 39 is sprung inwardly somewhat when the handle is applied so that the cabinet bears resiliently against the chassis and against the boss 45 so that the pins 51 are resiliently drawn into the grooves 52. The lower portion of the cabinet has a snug fit upon the lower chassis structure so that a rigid assembly is very readily obtained.

10 The tray 43 is preferably of octagonal shape, having four relatively short sides 53 at its corners.

15 The tray is preferably provided with depending skirt elements 54 below the sides 53, which obscure the view below the tray and offer practically no resistance to the escape of air from the openings 38.

20 Suitable controls are mounted on the chassis and are adapted to be operated through the cabinet. For example, I show at 55 a switch lever adapted to be passed through a suitable opening in the cabinet top. I have also shown a volume control 56 which comprises a stem 57 25 also adapted to pass through an opening in the top of the cabinet. A readily removable knob 58, preferably of pull off and push on type, may be mounted on the stem 57 to actuate same.

25 It will readily be understood that the removal 30 of the cabinet from the chassis and the reassembly of these elements is very easily and rapidly accomplished. An important advantage of the invention resides in the ease of the assembly of the chassis in the cabinet. The assembly of the 35 chassis in the cabinet, even under the best factory conditions, has heretofore been an expensive operation, ill adapted to mass production methods. According to the present invention this assembly is a matter of seconds, may be accomplished without tools, and is so simple that the chassis and cabinet may be shipped separately to be assembled later by the retailer or purchaser.

40 Although the invention has been described in connection with the specific details of a preferred embodiment it must be understood that such details are not intended to be limitative of the invention except insofar as set forth in the accompanying claims.

45 Having thus described my invention what I claim is:

1. A cabinet for a radio receiving set comprising a rigid top, flared channel strips secured to the top and extending at right angles thereto, a substantially tubular wall member adapted to be slid into engagement with the channel strips, and means for securing the wall member to the channel strips.

2. A cabinet for a radio receiving set, comprising a rigid top, rigid side members extending downwardly therefrom in spaced relation, a wall unit of fibrous material adapted to be inserted within the side members, a strap adapted to engage the lower ends of the side members, and means extending through the side members, wall units and straps securing same together in assembled relation.

3. A radio receiving set comprising a chassis having decorative feet adapted to stand on the floor, a cabinet adapted to be applied over the chassis from above, means associated with the feet against which the cabinet abuts, and means passing through the top of the cabinet and securing same to the chassis.

4. A radio receiving set comprising a chassis having decorative feet adapted to stand on the floor, a cabinet adapted to be applied over the chassis from above, means associated with the feet against which the cabinet abuts, a handle passing through the top of the cabinet and securing same to the chassis, a control mounted on the chassis having a stem extending through the cabinet, and an exterior knob mounted thereon, the handle and the knob being easily detachable manually.

5. A radio receiving set cabinet comprising a top, corner posts secured thereto, a wall unit defining walls extending between said corner posts, and a fabric covering for said wall unit having a free edge concealed by one of said posts.

6. A radio receiving set comprising a chassis adapted to stand on the floor, a loud speaker mounted adjacent one side thereof, a cabinet adapted to enclose the loud speaker, the chassis and cabinet being adapted for the upward passage of air, and opposite sides of the cabinet being provided with openings for the emission of sound waves, and a plate substantially closing the bottom of the set provided with openings for the admission of cooling air, said openings in said plate being located adjacent the side opposite the loud speaker.

7. In a radio receiving set a chassis comprising essentially a channel having its side flanges severed and its base bent to provide an L-shaped member, and plates secured to the severed flanges adapted to maintain the L-shaped relationship.

8. In a radio receiving set, a chassis of substantial L-shape comprising a channel having severed flanges, the base of the channel being bent about the line joining said severances, plates reinforcing the channel adjacent its corner and leg members mounted on the flanges of one portion of the channel.

9. In a radio receiving set an L-shaped chassis consisting essentially of two channels secured together substantially at right angles, and feet members secured to the flanges of one member and providing surfaces projecting beyond said flanges so as to provide abutments for a cabinet.

10. In a radio receiving set a chassis comprising an L-shaped channel member bent to provide two members at right angles, the channels of both members being in free communication.

11. In a radio receiving set a chassis comprising two channels arranged with their main webs in angular relation and their side webs outwardly directed, said channels defining a continuous angular passage between said side webs, and means holding said channels in said angular relation.

12. In a radio receiving set a chassis comprising two channels arranged with their main webs substantially at right angles and their sides outwardly directed away from said right angle, said main webs having ends located adjacent each other whereby a free substantially L-shaped passage is defined between said webs.

13. In a radio receiving set a chassis comprising two channels arranged with their main webs substantially at right angles and their sides outwardly directed away from said right angle, said main webs having adjacent ends located ad-

jacent each other whereby a free substantially L-shaped passage is defined between said webs, and reinforcing plates secured to said channels maintaining them in rectangular relation.

14. A cabinet for a radio receiving set comprising a rigid top, flared channel strips secured to the top and extending at right angles thereto, a wall member comprising flat portions of relatively weak material united at corners to form a tubular wall unit adapted to be slid within the channel strips with said strips overlying said corners to protect same from injury.

15. In a radio receiving set, a chassis comprising an L-shaped channel bent to provide two members at right angles, the channels of both members being in free communication, one of said channel members being vertical, and a cone type loud speaker mounted on the vertical channel and having its cone within the vertical channel.

16. In a radio receiving set, a unitary chassis comprising a vertical channel-shaped member, a cone type speaker carried by the vertical web of the channel member with the cone of the speaker extending into the channel of said member, control and indicating means carried by the upper end of said channel member, a cabinet structure adapted to surround the chassis and having an opening in a vertical wall thereof, and means for connecting the cabinet structure and chassis with the wall opening in the cabinet in registration with the channel in said channel-shaped member for the emission of sound from said speaker.

17. In a radio receiving set, a chassis comprising a vertical channel-shaped member, a cone type speaker carried by the vertical web of said channel member, control and indicating means carried by the upper end of said channel member, and a cabinet structure surrounding said chassis and having a sound emission wall portion extending across the open side of said channel member in lateral spaced relation to the speaker carrying web thereof.

18. In a radio receiving set, a chassis comprising a vertically elongated channel-shaped member, a cone type speaker carried by the vertical web of said channel member, a cabinet structure surrounding said chassis and having a sound emission opening in a vertical wall thereof and an opening at its bottom, control and indicating means carried by the upper end of said channel member, and means connecting said cabinet structure and chassis with said sound emission opening laterally spaced from the web of said channel member and in registration with said speaker.

19. In a radio receiving set, a chassis comprising a vertically elongated channel-shaped member, a cone type speaker carried by the web of said channel member and having its cone within the vertical channel of said member, a cabinet structure surrounding said chassis and having a wall extending across the open side of said channel member, said wall having openings in registry with the speaker and said channel having openings therein for the passage of sound therethrough, and control and indicating means carried by the upper end of said channel.

EDWARD F. ANDREWS.
